UNITED STATES PATENT OFFICE.

FREDERICK F. GAINES, OF SAVANNAH, GEORGIA, ASSIGNOR TO AMERICAN ARCH COMPANY, OF NEW YORK, N. Y., A CORPORATION OF NEW YORK.

LOCOMOTIVE FIRE-BOX.

1,115,801.

Specification of Letters Patent.

Patented Nov. 3, 1914.

Application filed July 24, 1913. Serial No. 780,985.

To all whom it may concern:

Be it known that I, FREDERICK F. GAINES, a citizen of the United States, and a resident of Savannah, county of Chatham and State of Georgia, have invented certain new and useful Improvements in Locomotive Fire-Boxes, of which the following is a specification.

The object of my invention is to increase the fuel economy and efficiency in relatively large fire boxes and to this end I divide the large fire box into a number of subsidiary combustion chambers by means of refractory walls and baffles, and I drive the burning gases from one to another of these chambers, causing the gases to be whirled and turned over and over in this movement, whereby the gases are intermingled and mixed and the fuel particles and gases are brought into immediate contact with the oxygen. This construction of walls and baffles serves to retard the escape of the gases from the fire box sufficiently to permit the thorough and complete oxidation of all of the fuel before the gases of combustion enter the flues. These baffles and walls also serve to cause the flowing gases to impinge directly upon and travel in contact with substantially all of the interior surfaces of the fire box, thereby obtaining a maximum efficiency in the transmission of heat through the walls of the fire box to the water in the boiler. I further increase the efficiency of the construction by forcing air through the dividing walls and causing it to enter into the burning gases in heated condition at many points in different parts of the fire box, whereby the combustion of the fuel is more thoroughly effected.

Primarily, I divide the large fire box into a forward auxiliary chamber and a rear main chamber by means of a refractory cross wall spaced from the flue sheet and I divide the main chamber into two parts by means of a central longitudinal wall extending from the cross wall to the rear sheet and both of the dividing walls rising somewhat more than half the height of the fire box. Each of these parts of the main combustion chamber is provided with a grate and with a fuel door, and I cover the forward end of each of them by means of an inclined refractory baffle wall or arch which rests upon or in contact with the upper edges of the cross and longitudinal walls.

These baffles cause the rising fire box gases to be forced to the rear end of the fire box where they flow upwardly against the crown sheet, and thence they flow longitudinally through the fire box to the forward end thereof, flowing over the upper surfaces of the baffle walls and over the cross wall to the forward auxiliary combustion chamber. As this auxiliary chamber is much larger in cross sectional area than the space above the baffle walls, the speed of the gases is greatly reduced therein and they are caused to deposit, in the auxiliary combustion chamber, the fuel particles which they may have carried over from the main combustion chamber. A fire box divided as described is thus composed of a series of combustion chambers, and, as the gases flow from one to another, they are caused to whirl and roll and be thoroughly intermingled and intermixed. For the purpose of introducing heated air into the gases as they rise from the grate, I provide vertical gas passages in the cross wall and in the longitudinal wall opening at their lower ends into the ash pit, and at their upper ends into the fire box, and the strong forced draft, which is made use of in such boilers, causes the air to flow upwardly through these passages and be discharged into the partially consumed gases rising from the fuel beds. As these walls soon become highly heated the injected air absorbs heat from the walls, as it flows upward through the vertical passages, and it is consequently forced into the fire box in a highly heated state, thereby serving to assist in the thorough and complete combustion of the fuel.

My invention will be more readily understood by reference to the accompanying drawings forming a part of this specification and in which:

Figure 1 is a vertical longitudinal central section of a locomotive fire box, constructed in accordance with my invention and taken on the broken line 1—1 of Fig. 2; Fig. 2 is a horizontal section of the fire box taken on the line 2—2 of Fig. 1; Fig. 3 is a vertical transverse section of the fire box on the line 3—3 of Fig. 1, one baffle wall only being shown; and Figs. 4, 5 and 6 are detail perspective views of the bricks of which the vertical walls are built.

A fire box A as shown in the drawings

comprises an open bottom steel chamber having a top wall and side and end walls. The forward end wall a^1 is the flue sheet, from which flues a^2 extend forwardly 5 through the boiler. The rear end wall a^3 contains a fuel door or opening a^4 one for each side of the fire box, side walls a^5 connect the front and rear walls together, and the top wall, or crown sheet a^6 , unites all 10 of the side and rear walls. I provide a rigid cross bearer or bridge member B which extends across the fire box and is spaced rearwardly from the flue sheet. I support this rigid member B in position substantially 15 level with the grate by bolting its ends to the mud ring C which closes the lower ends of the boiler water legs D. This bridge member B serves not only to support a refractory cross wall E but also to support 20 the forward end of a longitudinally arranged bridge member or bearer F which I place substantially midway between the side sheets of the fire box and which extends from the bridge member B to the rear end 25 of the fire box. This longitudinal bearer is also substantially level with the grate. The forward end of the bearer member F is bolted to and supported by the bridge member B and its rear end is secured to the mud 30 ring C. The fire box is provided with a suitable grate which is supported upon the side sheets and upon the bearer member F. Upon this bearer member F I support a longitudinal refractory wall G which extends 35 from the cross wall E to the rear wall or sheet of the fire box. These vertical walls, as shown in Fig. 2, extend upwardly somewhat above the middle of the height of the fire box and serve to divide the fire box 40 A into a forward auxiliary combustion chamber A^1 and two main combustion chambers A^2 . I cover over the forward ends of the chambers A^2 by means of rearwardly inclined refractory baffles or arches H which 45 rest upon or in contact with the cross wall E and are supported by the longitudinal wall G and the side sheets of the fire box, and I thereby provide what may be termed a fourth combustion chamber A^3 between 50 the baffle walls and the crown sheet of the fire box and connecting the main combustion chambers A^2 with the forward auxiliary chamber A^1 . Without the means of adding free air to the burning gases, to be described 55 herein, the division of the relatively large fire box into the several connected combustion chambers serves the purpose of causing the gases to be thoroughly intermingled and mixed and to be retarded in their passage 60 from the fuel bed to the flues.

The cross wall E is built up of several horizontal rows of refractory bricks e^1 . In the wall illustrated in the drawings there are three of these horizontal rows of bricks, 65 the first row e^2 rests upon the cross barrier

or bridge member B. This bridge member is of equal width with the bricks and is provided on its rear edge with an upstanding flange b^1 against which the first row of bricks contacts. These bricks are provided 70 on their upper surfaces with central longitudinal tongues e^2 and upon their lower surfaces with complementary grooves e^3 to receive the tongues of the bricks constituting the row next below. Each of these 75 bricks is provided with two vertical central passages e^4 spaced apart longitudinally of the brick and these passages are so proportioned and placed in relation to the length of the brick that when the bricks of alternate rows are arranged to break joints as shown in the drawings, the passages e^4 in one end of the bricks, constituting one row, register with the similar passages in the 80 opposite ends of the bricks constituting the rows of brick above and below, whereby vertical passages e^5 are formed in this cross wall. The upper row of bricks e^7 , of which the cross wall is composed, has a large central opening e^8 which registers with two 85 openings in the row of bricks below and is provided with a side opening e^9 to permit the discharge of the air, which rises through the passages, into the firebox immediately below the forward ends of the baffle walls H 90 as clearly illustrated in Fig. 3. The bridge member B is provided with openings b^2 registering with the vertical openings in the wall E and permitting the air to enter these 95 passages from the ash pit of the fire box. For the purpose of assisting in maintaining this cross wall E in position, I provide a buck stay plate J which is secured to the forward wall b^3 of the bridge member B and rises to a height substantially equal to the 100 height of the wall E. This plate extends across the firebox from side to side and contacts with the forward face of the wall E. The lower row of bricks of the wall E is thus held between the flange b^1 on the 105 bridge member B and the buck stay plate and the upper rows of bricks in the wall B are interlocked with this first row and contact with the buck stay plate and are thereby held in position. The wall is finished 110 on its upper edge by means of non-perforated bricks e^{10} having tongues e^{11} on their lower sides adapted to enter complementary grooves e^{12} in the bricks of the upper row e^7 and thus be held in position. Each brick, 115 in the wall E, as thus constructed, interlocks with several others, most of them interlocking with four other bricks of the wall.

The longitudinal wall G is constructed 120 similarly to the wall E except that the row of bricks g^1 which correspond to the row e^7 in the wall E are arranged to discharge alternately into the right and left hand combustion chambers A^2 as shown in Fig. 1 and 125

the top or cover row of bricks g^2 are considerably wider transversely of the firebox than the thickness of the wall G forming what may be termed a coping which projects at each side of the wall. The openings g^4 in the bricks g^1 discharge the heated air immediately below this coping and substantially along a medial line in the firebox, that is, substantially midway between the grate and the crown sheet. The bridge member F , similar to the bridge B , is provided on each side with an upstanding longitudinal flange f^1 which provides the upper surface of this bridge member with a longitudinal channel f^2 adapted to receive the lower row of bricks of the wall and retain them in position. These bricks are similar to the bricks of which the wall E is composed and are provided with interlocking centrally arranged tongues and grooves and the several rows of the wall are thereby maintained in position, the individual bricks of alternate rows being arranged in break joint position similar to the arrangement of the bricks in the wall E . The bridge member F is also provided in its upper wall with openings f^3 registering with the lower ends of the passages g^5 formed by the passages in the individual bricks and thereby the air is permitted to enter these passages from the ash pan. The coping bricks g^2 are provided with oppositely disposed downwardly inclined edge surfaces g^6 adapted to receive the inner ends of the bricks h^1 of which the arches H are composed. These arches as illustrated in the drawings comprise a series of pairs of bricks h^1 which are arranged in inverted V form, the inner edges of the arches resting upon the inclined surfaces g^6 of the coping and their outer edges being supported upon suitable lugs or supports h^2 secured to the side sheets a^5 of the firebox. The bricks h^1 are arranged in pairs and the upper ends of the individual bricks h^1 are provided with integral interlocking parts by which the bricks of each pair mutually retain each other in position.

The combustion gases in rising from the fuel beds in the chambers A^2 are forced upwardly by the strong drafts commonly used in locomotives at the present day and some of these gases impinge with considerable force on the undersides of the arches H . At this point they meet the incoming heated air through the openings e^9 and intermingle therewith. These incoming streams of air at the forward ends of the combustion chambers A^2 not only serve to provide additional oxygen for the combustion for the rising gases, but also serve to cause these gases to move rearwardly under the arches and to set up a whirling motion causing the gases as a whole to be thoroughly intermingled and mixed. As these gases progress to the

rear ends h^3 of these arches they meet air being delivered from the longitudinal wall through the openings g^4 and are further caused to change their direction of motion and be more thoroughly commingled. 70 These rearwardly moving gases at this point intermingle with the gases rising directly upward from the rear portions of the combustion chambers A^2 and pass upwardly toward the crown sheet between the rear edges of the arches H and the rear sheet of the firebox. All of the combustion gases are therefore forced toward the rear end of the box in order to rise toward the crown sheet whence they flow forward through the passage A^3 toward the front end of the firebox. 80 As these gases flow forwardly in the firebox, they enter the auxiliary combustion chamber A^1 from the passage A^3 and are therefore permitted to expand and the speed of the gases is consequently greatly reduced. 85 Their rate of flow before they enter the auxiliary chamber A^1 is ordinarily sufficiently rapid to cause them to carry more or less cinders and small fuel particles, but upon entering the auxiliary combustion chamber A^1 their rate of flow is reduced to such a point that they deposit their burden of cinders and fuel particles therein, and, for the purposes of conveniently cleaning this auxiliary combustion chamber A^1 , I provide it with a hoppered bottom a^7 which causes the falling particles to be collected in the middle portion thereof and I provide a cinder outlet a^8 normally maintained 90 closed by means of a cover plate a^9 . This cover plate is arranged to be opened from time to time to permit the removal of the accumulation of cinders and fuel particles. I preferably provide the hoppered bottom a^7 with a refractory lining a^{10} to protect the walls thereof. The flues a^2 lead forwardly from this auxiliary combustion chamber A^1 and the action of the combustion chamber in causing the settling of the fuel particles and cinders out of the gases provides what may be termed a practical spark arrester, furthermore the rolling or whirling of the gases as they pass over the upper edge of the wall E serves to direct the cinders and unburnt fuel particles toward the bottom or lower end of the auxiliary combustion chamber A^1 and thereby assist their deposit therein and the gases consequently pass into the flues substantially free from any of these 105 particles. 110

As many modifications of my invention will readily suggest themselves to one skilled in the art I do not limit or confine my invention to the specific structures herein shown and described. 125

I claim:

In a locomotive boiler firebox a refractory cross wall rising from the level of the grate extending from side sheet to side sheet and 130

spaced from the flue sheet and dividing the combustion chamber into a rear main chamber and a forward auxiliary chamber, a longitudinal refractory wall also rising from 5 the level of the grate and dividing the main combustion chamber into two parallel subsidiary chambers, each of said walls being adapted to discharge heated air into the firebox from discharge openings arranged near 10 their upper edges, rearwardly and upwardly inclined refractory baffle walls covering the forward ends of said subsidiary combustion

chambers, and a hoppered bottom in said auxiliary chamber for the collection of cinders and unburned fuel particles carried 15 over by the gases of combustion.

In testimony whereof, I have hereunto set my hand, this 27th day of June, 1913, in the presence of two subscribing witnesses:

FREDERICK F. GAINES.

Witnesses:

J. R. KOERPER,
J. G. KELLAM.
